UNITED STATES PATENT OFFICE.

KIICHIRO USUI, OF SHIZUOKA-KEN, JAPAN.

MECHANICAL STOKER.

Application filed November 15, 1919. Serial No. 338,208.

To all whom it may concern:

Be it known that I, KIICHIRO USUI, a subject of the Emperor of Japan, and a resident of No. 169 Minami-Ando, Toyoda, Abe-
5 Gun, Shizuoka-Ken, Empire of Japan, have invented new and useful Improvements in Mechanical Stokers, of which the following is a specification.

This invention relates to improvements in 10 mechanical stokers of the type in which the grate bars move from end to end, the object of the invention being to provide an improved stoker of this type embodying novel means for successively dropping the 15 grate bars at the rear end of the grate and for carrying them forwardly and reinstating them for use at the front end of the grate, and also embodying means of novel construction for regulating the draft of air 20 under and between the grate bars.

With the above and other objects in view the invention resides in the construction, combination and arrangement of parts hereinafter described and claimed.

25 In the accompanying drawings:—

Fig. 1 is a central longitudinal sectional elevation of a preferred form of mechanical stoker in accordance with my invention.

Fig. 1^a is a similar view of the rear portion of the grate.

Fig. 2 is a front elevation, partly in section, on the plane indicated by the line 2—2 of Fig. 1.

Fig. 3 is a transverse section taken on the 35 plane indicated by the line 3—3 of Fig. 1.

Fig. 4 is a detail perspective view of a portion of one form of grate bar.

Fig. 4^a is a similar view of a portion of 40 another modified form of grate bar.

Fig. 4^b is a similar view of a portion of another modified form of grate bar.

Fig. 4^c is a similar view of a portion of 45 still another modified form of the same.

Similar reference numerals refer to like parts throughout the several views.

Automatic stokers may be generally divided into two classes, one in which the fire grate is arranged in the form of an endless movable chain, and the other in which the 50 grate bars move back and forth longitudinally of the furnace. The former while possessing better feeding efficiency of the fuel often has defects necessitating frequent repairing. The latter while requiring no fre-

quent repairing has heretofore been not 55 satisfactory as to the feeding of the fuel.

With the object of removing the difficulties experienced with both classes of the stokers above referred to, and yet obtaining the full advantages attached thereto, I have 60 invented a stoker hereinafter described which will work satisfactorily and which combines the advantages possessed by both such classes of stokers.

The combustion chamber of the furnace 65 is not here shown. It may occupy the space indicated at 1. The stoker is supported from underneath by two opposing girders 2, the lower ends of which rest upon suitable rollers 3 adapted to move back and forth 70 upon a corresponding railway 4, in order to facilitate cleaning and repairing when required.

In some instances, instead of being mounted upon rollers or wheels, each girder 75 2 may be conveniently secured to the side wall of the combustion chamber or otherwise rigidly secured to the flue for instance, of the Cornish or Lancashire boilers.

Upon the inner opposing walls of the girders 2, at the upper portions thereof, are secured stationary rails 5 adapted to receive thereon a set of grate bars, the construction of which bars 6 may vary according to the nature of the fuels, for instance in cases in 80 which coal is used as fuel in a combustion chamber of considerable breadth, preferably a bar, such as shown in Fig. 4 at A, having a serrated portion between the spaced ribs so as to secure better ventilation may be 85 employed. Other forms such as shown at B in Fig. 4^a, or at C in Fig. 4^b, or at D in Fig. 4^c, may be employed, according to conditions.

Bar conveying means are provided which 90 consist of a set of reciprocating rails 7 arranged under the stationary rails 5, and which are mounted on suitable rollers 19. Vertical plates 8 having inclined front ends, are secured to the rear ends of the reciprocating rails 7 and extending forwardly and downwardly from the rear ends of the stationary rails 5 afford the means for receiving on said inclined front ends the grate bar 100 dropped from the rear end of the fire grate, thereby causing the said bars to slide down along the said inclined ends of the plates 8 and to rest on the rear portion of the hori- 105

zontal ribs of the conveyor rails 17 which are secured to the girders 2, and positioned above the reciprocating rails 7.

At the front end portion of each reciprocating rail 7 is provided a lever 9, the lower end of which is fitted with a suitable roller 10 adapted to engage with and capable of sliding back and forth upon the roller track 12 by means of a link 11 which is pivotally connected with and extends between the reciprocating rails 7 and the roller 10, as shown in Fig. 1.

The action is such that in the downward movement the upper end of the lever 9 will be placed in position ready to receive thereon the grate bars shifted from the conveyor rails 17, whilst in the upward movement this lever 9 will assume the position adapted to raise the grate bars and deliver them in succession on to the stationary rails 5, as will appear later.

The means for reciprocating the rails 7 may be any suitable transmission mechanism which may be conveniently arranged in the front portion of the apparatus, the description of which will appear later, and which may be operable through the medium of a connecting rod 13 extending between and connecting the lower part of each reciprocating rail 7 and the said transmission mechanism so as to cause the latter rail 7 to move back and forth, thereby communicating the motion to cause the lever 9 to be elevated or depressed over the roller track 12, thus effecting the receiving and delivering of the grate bars between the reciprocating rails 7 and stationary rail 5.

The transmission mechanism may be arranged in any suitable manner, and in the drawings I have shown by way of example a shaft 14 adapted to operate the connecting rods 13 through the medium of intermediate gearing such as worms, worm wheels, cranks, etc., as will be necessary to produce the above effect.

To cause the elevated grate bar to be transferred from the cam levers 9 onto the stationary rails 5 there are provided thrust rods 16 adapted to move back and forth by means of cams 15, likewise operable through the medium of the same aforesaid transmission mechanism.

The grate bars which drop from the rearmost end of the fire grate and which lodge upon the rear end of the reciprocating rails 7 after sliding down the slant faces of the inclined plates 8, are conveyed forward one after another successively and step-by-step.

To this end there are provided underneath the stationary rails 5 or otherwise pivoted to the web portions of the same, a plurality of pawl members 17' equally spaced, and inclined downwardly and forwardly so that the free lower end of each member 17' may, at a certain angle, bear

upon the upper side of the horizontal webs of the conveyor rails 17.

The reciprocating rails 7 are likewise provided at intervals with a plurality of inclined plates 18, by which the grate bars are enabled to move forward one after another simultaneously with the forward movement of the reciprocating rails 7, action being transmitted from the connecting rods 13. The operation is such that upon the backward movement of the reciprocating rails 7, all the grate bars with which the lower free ends of the pawl members 17' engage are caused to remain stationary upon the conveyor rail 17 allowing the reciprocating rails 7 alone to move backward, whilst upon the forward or return movement of the reciprocating rails 7 all the grate bars with which the front edges 18' of the inclined plates 18 engage are caused to move forward by lifting above them the free ends of the pawl members 17' simultaneously with the movement of the reciprocating rails 7 so as to allow each of the grate bars to traverse the distance corresponding to the space between the pawl members 17' at the completion of one reciprocating movement of the reciprocating rails 7.

It will be understood that as each grate bar reaches the front ends of the conveyor rails 17, it will be above and in the paths of the levers 9, so that said levers in their ensuing forward upward movement will raise said grate bar to the required position above the rails 5 and said grate bar will be pushed in place on said rails 5 by the rods 16. This will cause the rearmost fire bar to be dropped from the rear end of the grate, thence sliding down along the slant face of the inclined plates 8 until eventually deposited at the front of the rearmost inclined plate 18. Upon the following forward movement of the reciprocating rails 7 the grate bar so positioned at the front of the rearmost inclined plate 18 will be then pushed forward by the front edge of the rearmost inclined plate 18 so as to occupy the position adjacently preceding the rearmost pawl members 17', and so on, as will be readily understood.

The feeding of the fuel may be effected through the hopper 19' located above the front end of the fire grate, regulated by a suitable adjustable door 20 through which an appropriate quantity of the fuel is allowed to pass into the front end of the fire grate.

The means for regulating the draft of the air may comprise a plurality of dampers 22 which are preferably pivoted to the lower part of the stationary rails 5 and connected by a connecting rod 23. Said rod is connected at one end with the oscillating lever 24. An actuating rod 26 is connected as at 25 to the said oscillating lever 24 and en-

ables the lever 24 to be moved as required to elevate or depress the dampers 22, thus regulating the draft.

What I claim is:—

- 5 In a mechanical stoker, supporting rails, grate bars mounted for sliding movement on said rails, conveyor rails arranged below the supporting rails, elements at the rear ends of the supporting and conveyor rails, presenting downwardly and forwardly inclined surfaces to cause grate bars, as they successively leave the rear ends of the supporting rails to be directed by said inclined surfaces downwardly and forwardly onto the 10 rear portions of the conveyor rails, downwardly and forwardly inclined pivoted pawls bearing at their lower ends on said conveyor rails, a reciprocating element having plates with inclined upper sides, to facilitate the passage of grate bars thereover 20 and on the forward strokes of said element to engage and move the dropped grate bars forwardly, step-by-step, means at the front ends of the supporting and conveyor bars, to successively raise the grate bars from the 25 conveyor bars, and means to force the raised grate bars rearwardly on the supporting bars.
- 15 In testimony whereof I affix my signature in presence of two witnesses.

KIICHIRO USUI.
